UNITED STATES PATENT OFFICE.

SIMON DOKK OLSEN, OF LONDON, ENGLAND, ASSIGNOR TO THE OLSEN ENGINE SYNDICATE LIMITED, OF LONDON, ENGLAND, A BRITISH COMPANY.

MEANS FOR INJECTING LIQUID FUEL INTO INTERNAL-COMBUSTION ENGINES.

Application filed March 18, 1925, Serial No. 16,457, and in Great Britain April 30, 1924.

This invention has reference to means for injecting liquid fuel into internal-combustion engines of the type in which an explosive charge is formed in a small injector cylinder connected with the working cylinder, and is forced into the latter by a spring-pressed plunger which is retracted by a cam after each injection stroke.

The invention relates more particularly to arrangements of this kind in which a portion of the compressed air in the working cylinder enters the injector cylinder and after mixing with the liquid fuel or oil to form the charge, is driven back into the engine cylinder by the plunger.

The main object of the invention is to ensure more perfect formation or atomization of the charge and more efficient distribution and ignition thereof in the working cylinder, this being attained by a "double action", that is to say the charge in the injector cylinder being formed in two stages as it were, one stage during the backward stroke of the plunger, and the other during its forward stroke.

To this end according to one example or construction, of such a double-action injector, which is specially intended for small engines working on the Diesel principle, the plunger is combined with an independently-moving valve for closing the passage to the injector cylinder, this valve having also an extension piece with a head or enlargement acting both as a spreader and distributor and also as a throttling device for the orifice by which the charge finally enters the cylinder.

Another example or construction is intended primarily for use with two-stroke engines to obviate the waste in the latter due to the unavoidable carrying away of fuel oil spray or vapour along with the exhaust. It may however be applied to four-stroke engines if desired, and may be used both with light-oil, paraffin or spirit, and also with heavy oil. It may be used with either low or high compression and with spark-plug ignition, or in engines having self-ignition on the Diesel principle.

In this construction the injector cylinder is double-ended, the oil or liquid fuel being taken in above the piston and then forced into the space below the piston as the latter rises, through a suitable port or by-pass. As it is discharged into the lower part of the

cylinder, it mixes with the air therein which has just come from the engine cylinder, and the mixture is forced out as the piston descends, being sprayed into the engine cylinder for ignition as the working charge in 60 the usual way.

In the accompanying diagrammatic drawings:

Fig. 1 represents a longitudinal section of an arrangement suitable for a Diesel engine, 65 and

Fig. 2 illustrates a detail thereof.

Figs. 3 to 7 are diagrams showing the parts at different stages of the working stroke.

Fig. 8 illustrates the arrangement as applicable to a two-stroke engine.

Referring more particularly to Fig. 1:

a represents the top or end of the engine cylinder, *b* the injector cylinder which is in 75 the form of a hollow block or plug firmly secured therein, *c* being the injector plunger and *d* the spindle of the independent valve *e* which works down the centre of said plunger *c*.

At the lower end of the valve *e* is the conical head *f* which spreads or scatters the charge as it enters the combustion chamber *g* (Fig. 6) of the engine. This head is carried by a short stem or extension piece *f*¹ 85 central with the valve *e*. In addition to the head the stem may have lateral flanges or projections to assist the atomizing.

h is the passage from the injector chamber or cylinder *b* into the working cylinder *a*. It is arranged centrally in a disc or block *b*¹ which is screwed on the bottom of the cylinder *b* and forms the end cap thereof.

This passage *h* is made in two parts of different diameters. In the wider part the above valve *e* works, whilst the narrower part is adapted to receive the head *f* of the throttling device and spreader. The mouth *h*¹ of the passage forms the actual injection orifice.

The shoulder *h*² between the two parts of the passage *h* forms the valve seat and from a point at one side of it an inclined tangential by-pass *i* (see also Fig. 2) leads up towards the side of the injector chamber near the opening *k*¹ of the inlet passage or passages *k* through which the oil is fed in under pressure by a suitable pump, so that air coming up the by-pass will strike the oil and pulverize it.

The valve-spindle d extends axially through the injector plunger c and both of them are adjustable and are operated independently for instance through levers d^1 and d^2 , being retracted by separate cams, and returned to give their working stroke by springs. These cams and springs are not shown for the sake of clearness, their action and arrangement being obvious.

10 The parts are so timed that when the plunger c has completed its forward working or injecting stroke, the valve e (see Fig. 3) is also in its forward and closed position, and the conical head or projection f which it 15 carries is thrust out slightly into the engine cylinder towards the working piston a^1 .

10 The valve e and spreader f remaining in this position, the plunger c retires slightly (see Fig. 4) and a small quantity of oil 20 enters the device through the inlet passage k after the commencement of the movement 25 of the piston a^1 toward the right.

25 The plunger c then makes a further backward movement (see Fig. 5) to ensure the reduction and elimination of any residual 30 pressure in the device, whilst the valve e opens to its fullest extent, and allows compressed (and therefore hot) air from the engine cylinder, due to the piston a^1 continuing the compression stroke, to flow 35 through the by-pass i into the injector chamber b , where it strikes the oil which has just entered by k , and partly forms it into a spray or vapor, at the same time heating 40 it. This is the first stage of the formation of the charge.

40 The valve e then half closes (see Fig. 6) so that the sprayer-head f lies right in the injector orifice h^1 and partly closes or throttles it. At the same time the main or injector plunger c moves forward and the partly formed charge is driven through the by-pass i and thence through the throttled orifice h^1 , whereby the atomization becomes 45 very complete and the charge is forced into the cylinder and past the conical head or sprayer f with a whirling spiral motion due to the tangential position of the passage.

50 This finishes the second stage of the formation of the charge. As the latter enters the working cylinder, the explosion takes place spontaneously owing to the heat due to the compression, in the well-known manner.

55 The valve e then closes (see Fig. 7) and shuts the injector off completely from the working cylinder, and both it and the valve remain at rest till the end of the working stroke in the engine. The plunger then begins to retire, and the above operations are 60 repeated.

65 It will thus be seen that there is a clear double action as it were, the charge being partly formed as the air flows from the engine into the injector cylinder and the

formation being completed as the mixture returns in the opposite direction under the thrust of the injector plunger.

Referring to the arrangement shown in Fig. 8, the injector cylinder b is double-ended, the space above and below the plunger or piston c both taking part in the formation of the charge. The injector piston or plunger is unprovided with an independent valve and consists of a cylindrical block c rather more than half the depth of the injector cylinder b in which it works freely or fairly easily. The rod or stem c^2 of the piston passes out through a closed conical cover or gland b^2 . It is acted on by a powerful spring c^3 which tends to force the piston downward or forward and by a cam-actuated lever c^4 which moves it backward counter to the spring, as above mentioned. The cam may be of any suitable shape, as even a pear-shaped cam will allow the piston or plunger c to work sharply enough when the engine is running at full speed.

70 In one side of the cylinder is the oil-inlet orifice k which just clears the top of the plunger c when the latter is in its lowest position. In the opposite side but lower down is the discharge orifice from a by-pass i , which must clear the bottom of the piston when the latter is fully raised, (see dotted 75 lines). The ends of the plunger or piston may be made slightly inclined or askew so that by turning it round, the exact degrees of clearance at the orifice can be regulated or adjusted with great nicety. The side 80 of the piston c has a groove or recess in which is fitted a short piece or strip l which is pressed against the cylinder wall near the oil inlet k by springs l^1 . It serves (like a slide valve) to ensure proper closing of the 85 latter as the piston moves up and down, so that the closure is complete notwithstanding that the piston is an easy fit in the cylinder.

85 The fuel oil inlet pipe k may also be 90 graduated or controlled by a needle valve or as desired.

90 Centrally in the bottom of the injector is a conical opening h^1 through which the charge is forced into the engine cylinder. 105 This opening may resemble a small valve-seat, and the piston carries opposite to it, a central pin or finger f^1 which can enter it freely but has a conical or valve-like portion e^1 to fit this valve seat. When the piston 110 or plunger c is right down, the valve-like opening h^1 is closed entirely, whereas when the piston is drawn right up or backward, the pin or finger f^1 is withdrawn clear out of it (see dotted lines) and it is left fully 115 open. In intermediate positions the pin f^1 is in the opening and almost closes it, so giving a very restricted passage and ensuring good atomizing.

120 The by-pass i extends down through the 125

wall of the cylinder. It opens at one end into the top of the latter and at the other end into the bottom thereof; just below the raised position of the piston (see dotted line) as stated.

- When the piston *c* is right down, a small quantity of oil enters through the side inlet *k*. As the piston is drawn back or rises, its slide piece *l* first covers and closes the inlet *k*. The piston then carries the oil up to the top (which may be enlarged as shown at *b*²) and forces it into the by-pass *i*. The oil then passes down *i* to the under side of the piston *c* and is sprayed into the lower chamber of the cylinder, which in the meantime has become filled with compressed air from the engine cylinder. As the piston or plunger *c* descends or makes its forward stroke, it completes the mixture of oil-spray and air as it forces it back into the engine cylinder. At the same time it also covers and closes the by-pass *i*, so that as it continues to descend, a vacuum is formed at the top of the cylinder ready to receive or suck in the next charge of oil through the inlet pipe or port *k*.

It may be mentioned that the injector piston need only have a rather slack or easy fit in the cylinder, a fair amount of clearance being an advantage in fact in many cases. Thus the inconvenience of a tightly fitting or packed piston is avoided, and the wear and tear are correspondingly reduced. The only part which requires to be really tight is the slide-piece *l* controlling the oil inlet *k*. Obviously the above arrangements may be modified in various ways in carrying the invention into practice without departing from the general nature thereof.

I claim:

1. In a liquid fuel injector, the combination of an injector cylinder, a plunger working therein, means for supplying fuel to the space in front of said plunger, a by-pass

through which air is admitted from the engine cylinder at a point near the fuel inlet 45 for preliminary atomization of the fuel, and means carried by said plunger for restricting, during the actual injection, the passage leading into the engine cylinder, substantially as described.

2. In a liquid-fuel injector, the combination of an injector cylinder, an oil-supply opening to one end thereof, a valve-controlled inlet leading to the engine cylinder, a by-pass from said oil-supply opening to 50 near the valve seat, a plunger in which the valve stem works axially, a stem with an enlarged head for restricting the injection inlet, and means for operating the plunger and valve independently of each other, substantially as described.

3. In a liquid-fuel injector, the combination of an injector cylinder, an oil-supply opening into one end thereof, a valve-controlled inlet passage leading to the engine 65 cylinder for the flow of the charge one way and for that of compressed air the other way, a valve seat at the end of said passage remote from the engine cylinder, a by-pass from said inlet extending to near the valve 70 seat, a plunger, a valve spindle working axially therein, and a stem on said valve for restricting the inlet at the moment of the injection, substantially as described.

4. The combination of an injector secured 75 direct in the end of an engine cylinder, an inlet passage at the inner end of said injector leading direct to the engine cylinder and made of two different diameters with a valve-seat between them, a plunger working in said 80 injector, a valve for closing said passage, and a device for restricting the same during injection, substantially as described.

In testimony whereof I affix my signature.

SIMON DOKK OLSEN.
